CLAIM

The ornamental design for a blade holder, as shown and
described.

DESCRIPTION

FIG. 1 is a perspective view of a blade holder showing my
new design;

FIG. 2 is a front elevation view thereof;

FIG. 3 is a rear elevation view thereof;

FIG. 4 is a side elevation view thereof;

FIG. 5 is another side elevation view thereof;

FIG. 6 is a top plan view thereof; and,

FIG. 7 is a bottom plan view thereof.

The broken lines in the drawings depict portions of the blade
holder that form no part of the claimed design.

1 Claim, 7 Drawing Sheets
